Patent No. D483,649 S

Patented: December 16, 2003

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Paul M. Linford, Salt Lake City, UT; Duane M. Linford, Salt Lake City, UT; and Richard Smith, Salt Lake City, UT.

Signed and Sealed this Twenty-fifth Day of April 2006.
